DESIGN FOR AN ASH TRAY OR SIMILAR ARTICLE

Beth Weissman, New York, N. Y.

Application May 17, 1935, Serial No. 56,881

Term of patent 3½ years

To all whom it may concern:

Be it known that I, Beth Weissman, a citizen of the United States of America, residing in Manhattan, county of New York, and State of New York, have invented a new, original, and ornamental Design for an Ash Tray or Similar Article, of which the following is a specification, reference being had to the accompanying drawing, forming part thereof, wherein,

The figure is a front perspective view of the ash tray, showing my new design.

The ornamental rectangular frame, which is the regulation match-box container, mounted on the outer rim of the ash tray, as shown on the drawing, has an oval center insert.

I claim:

The ornamental design for an ash tray or similar article, substantially as shown and described.

BETH WEISSMAN.
